UNITED STATES PATENT OFFICE.

HERMANN EVERKEN, OF ESSEN, GERMANY, ASSIGNOR TO FRIED. KRUPP AKTIEN-
GESELLSCHAFT, OF ESSEN-ON-THE-RUHR, GERMANY.

ACID-RESISTING RECEPTACLE.

1,384,023.

Specification of Letters Patent.

Patented July 5, 1921.

No Drawing.

Application filed September 4, 1920. Serial No. 408,374.

To all whom it may concern:

Be it known that I, HERMANN EVERKEN, residing at Essen, Germany, a citizen of the German Republic, have invented a certain 5 new and useful Improvement in Acid-Resisting Receptacles, (for which I have filed an application in Germany, June 17, 1918,) of which the following is a specification.

This invention relates to acid resisting receptacles such as boilers, pipes and the like having an inner wall composed of acid resisting iron and an iron outer wall separated from the inner wall by an intermediate 10 space and the invention consists in casting 15 the intermediate space full of lead.

A constructional example of the receptacle forming the subject matter of the invention will be described below. The receptacle, which is intended in particular for holding hot concentrated nitric or sulfuric acid, has an inner wall composed of acid resisting cast silicon iron and an outer wall separated from the inner wall by an intermediate space, which outer wall is composed 20 of cast iron, which should be as acid resisting as possible. The intermediate space is 25

cast full of lead, which forms a perfectly tight connection between the silicon iron of the inner wall and the cast iron of the outer wall, so that cracks, which may easily occur 30 in the inner wall owing to the action of the temperature of the acid, which rises to from 100 to 300 degrees, are rendered harmless. The cast iron outer wall prevents at the same time any sagging of the leaden jacket 35 under the action of the pressure existing in the interior of the receptacle, which can transmit itself through the cracks to the leaden jacket.

Claim.

An acid resisting receptacle having an inner wall of acid resisting iron, an outer wall separated from the inner, and a filling of cast lead between said walls.

The foregoing specification signed at 45 Essen, Germany, this 11th day of June, 1920.

HERMANN EVERKEN.

In presence of—

HANS GOTTMANN,
JOSEF OLBERTZ.
